FURNACE ROOF OR ARCH WITH SELF-ADJUSTING MOUNTING FOR THERMAL EXPANSION

John Edward Pluck, Rotherham, England

Application April 16, 1945, Serial No. 588,427
In Great Britain March 23, 1944Section 1, Public Law 690, August 8, 1946
Patent expires March 23, 1964

8 Claims. (Cl. 110—99)

1

This invention relates to the roofs or arches of industrial furnaces for use at high temperatures and which are built up of bricks of refractory materials such as chrome magnesite, dolomite, and magnesite.

The main object of the invention is to provide improvements to the arched roofs of such furnaces whereby the roof life is considerably increased.

Refractories made of basic materials are most desirable for the building of all parts of furnaces working on the open hearth basic steel processes, because acid refractories cause undesirable re-actions with the vapours from the bath of metal. This invention is intended to overcome, or minimise such existing difficulties as spalling, iron oxide growth, and weakness under load at high temperatures. Magnesite, chrome-magnesite and dolomite expand evenly in proportion to temperature increase, and contract in proportion to temperature decrease, whereas silica (the normal roof material) possesses the property of almost completing its expansion below 600° centigrade.

It has previously been proposed to accommodate a small degree of outside expansion and a large degree of inside expansion by employing a roof buttress which is so pivoted on fixed axes carried by the lateral vertical furnace supports that all the necessary expansion can take place whilst at the same time any change of the roof radius is also accommodated.

In the case of the present invention, also, a pivoted roof supporting buttress is employed which accommodates small external and large internal expansions, but the invention has for its object to provide an improved construction or arrangement, which is characterised by several novel features. For example the load varies increasingly from cold to hot position so as to allow for variations in thrust due to changing radius of curvature. Further the buttresses at back and front on the furnace are coupled together, and weights are employed instead of springs to resist their movement, whilst the buttresses pivot about axes or slung fulcrums which are slidable along the lateral vertical furnace supports instead of being fixed in relation to said supports.

The invention also includes various important features of construction which may be summarised as follows:

At the back of the furnace each buttress is attached to a lever to which is connected a bell-crank lever rotatable about a fixed pivot. From

2

the free end of the bell-crank lever a weight bar is hung on which can be placed weights totalling the previously calculated amount necessary to balance the roof thrust loads, plus a small proportion as a safety factor.

The bell-crank lever is such that the leverage of the weight varies according to the position of the roof; thus, when the roof is cold and in its high position, the roof thrust is low, and when the roof is in its hot and lowest position the roof thrust is at its highest. Therefore, the variation of the weight leverage is to accommodate such differences of the roof thrust, plus a fixed slight proportion in excess for safety, all of which is applied automatically. This arrangement keeps the loads and the compressive stresses in the roof at the absolute minimum for stability. The possible weakness of chrome-magnesite bricks under compressive loads at high temperature is accordingly taken care of.

In order that the roof may be able to move in the above manner and yet be kept perfectly stable, the front roof buttresses are made to move in exactly the same way as, but opposite to, the

back by a system of levers and a tie-rod. Also through the same system of levers, the weights to balance the front roof thrusts are attached to the back weight bar, leaving only the smallest amount of gear at the front of the furnace.

Even if a roof is built with different levels at back and front, the movements of front and back buttresses can be of equal amounts or can be fixed at any proportion of movement at any angle.

The general arrangement is such that the main furnace front stays and back stays are not cut and thereby weakened by supporting bolt holes, but all the gear is suspended by additional members, fixed across the top cross-ties. This system of support will allow any excessive upward expansion of the back and front walls to lift the whole roof, together with the operating gear, thereby eliminating nipping forces between wall tops and roof which are liable to cause damage when the roof is fixed.

At the maximum temperature the roof buttresses will have their outer faces touching the upright furnace stays. In the case of an explosion in the furnace causing a hole in the roof, or for any other reason, which in turn causes damage to any or all of the gear, then the remaining part of the roof, providing it is kept hot, will stay in position.

In order that the invention may be clearly

5 10 15 20 25 30 35 40 45 50 55

understood and readily carried into practice it is illustrated, by way of example only, by the accompanying drawings, in which:

Figure 1 is a front to back cross sectional elevation of a construction of a furnace according to the invention.

Figure 2 is a front elevation of a section of the furnace showing two adjacent buttress ends.

Figure 3 is a rear elevation of a similar section of the furnace.

Figure 4 is a horizontal section on the line IV—IV of Figure 1 at a buttress junction.

Figure 5 is a horizontal section on the line V—V of Figure 1 at a buttress junction.

Figure 6 is a horizontal section on the line VI—VI of Figure 1 at a buttress junction, and

Figure 7 is a horizontal section on the line VII—VII of Figure 1 at a buttress junction.

Referring to the drawings the furnace brick-work 2 is supported by a steel bath receptacle 3 resting in bottom beams 4, and fitted with back stays 5, front stays 6 and top tie members 7. The roof bricks form an arch 8 extending across the furnace and supported by buttresses 11 at front and back of the furnace. These buttresses 11 are at least long enough to support a section of the roof 8 between any two sets of stays, and are so designed as to allow the brick arch 8 to subtend any included angle of approximately 60°, when hot, such an angle giving maximum stability under normal working conditions.

The buttresses 11 are bolted at 12 to the lower ends of levers 16 rocking on pivot shafts 13 journalled in bearings slidably mounted on adjacent pairs of back and front stays 5, 6. Said shafts 13 also pass through the lower ends of links 28, whose upper ends are mounted on shafts 33, 36, parallel to but above the pivot shafts 13, the upper shafts 33, 36, having their ends journalled in bearing brackets 37 slidably engaged with the aforesaid adjacent pairs of back and front stays so as to be capable of upward and downward movement due to excessive front and back wall expansion. Said bearing brackets 37 are suspended from top frame members 25 by rods 20 whose shanks are screw threaded and provided with washers 35 and nuts 24 so that by adjustment of the nuts 24 the bearing brackets 37 can be adjusted vertically. The central part of the upper shaft 33 at the front of the furnace carries a rocking lever 27 for each buttress lever 16, the lower end of which has a slot engaged with a pin or shaft 34 journalled in bearings bolted at 17 to the buttress lever 16, whilst the other arm of the rocking lever is pivotally connected at 32 to one end of the part 31 of a tie rod 29, 30, 31, extending across the arch to the back of the furnace, where the part 29 of the tie rod is articulated at 28 to the short arm of a bell-crank lever 19, which is mounted on a pivot pin or shaft 28 journalled in bearings fastened by bolts 11 on the buttress lever 16. The bell-crank lever 19 takes the place of the rocking lever 27 at the front of the furnace, being mounted on the upper of the two shafts i. e. the shaft 36 carried by the vertically sliding bearings 37, in a similar manner. The two parts 29, 31 of the tie rod are connected together by a right and left handed screw coupling 38 to allow adjustment of its length to suit site irregularities.

Hung at 23 from the long arms of the bell-crank levers 19 at the back of the furnace are suspension rods 21 for cheese type weights 22.

Since the buttresses 11 with levers 16 at the back of the furnace and their bell-crank levers 19

19 rotate about different fixed pivots and have different radii of action, but are connected together by the shaft or pin 28 projecting from the side of the buttress lever 16, the short arms of the bell-crank levers have a slot engagement with the projecting pin or shaft 28 to which the tie rod 31 is connected. When the furnace is cold the bell-crank levers 19 are in a position in which their short arms are effectively longer and the long arms are effectively shorter than when the furnace is hot, since when the furnace is hot the short arms are vertical and the long arms are horizontal, and the lever has its maximum leverage. Therefore the effective thrust on the buttresses 11 will be varied and adjusted to suit the varied movement of the roof during temperature changes.

The buttresses become fully supported by the back or front stays 5 and 6 when complete expansion has taken place, at which point further rotation is prevented by engagement of the outer surfaces of the buttresses with the back and front stays.

The proportions of the levers may be such that the necessary weights are very small in relation to the thrusts in the roof arches.

It should be understood that mechanism as described above is provided at each end of the buttresses 11, and the mechanisms for a pair of adjacent buttress ends are combined together, inasmuch as the upper shafts 33, 36, and the lower shaft 13 will be common, and the shafts or pins 28, 34 connecting the rocking and bell-crank levers with the tie rod 29, 31, which project from the side of the buttress levers 16 will be common to the pair of adjacent buttress levers, the pair of rocking and bell-crank levers 27, 19, associated with a pair of adjacent buttress levers 16, 16, being mounted side by side on the upper shaft 33 or 36 carried by the vertically adjustable bearing brackets 37.

In order to accommodate for increase in the radius of curvature of the roof arch 8 due to expansion when hot three beams 41 are provided longitudinally above the arch, one at the centre and two half-way between the centre and the front and back. These beams are not attached to the roof arch but simply make contact therewith in its various positions. They are arranged to rise and fall with the movement of the roof, being moved through bell-crank levers 47, 48 and 49 from the buttress levers 16, the lever arms being so proportioned as to have the same ratio as that of the vertical movement of the roof to the longitudinal movement of the tie rod 29, 31.

The beams 41 carry angle brackets 42, 43 and 44 which are slung by links 45 and pins 46 from the lower arms of the corresponding bell-crank levers 47, 48, 49 which are rotatably supported by brackets 50, 51, 52 fastened by bolts 53 to the main cross ties 7. The upper arms of bell-crank lever 47 of the front beam 41 are articulated to rods 54, the other ends of which are articulated to the pins 32 at the ends of tie bars 31.

The upper arms of bell-crank levers 48 of middle beam 41 are connected to short links 55 which are articulated to tie rod 29, 31 at 57. Similarly the upper ends of bell-crank levers 49, of rear beam 41, are connected to rods 56 which are also articulated to tie rod 29, 31 at 57.

Thus all three of the beams 41 take movement from the tie rod 29, 31 and as will be seen, the bell-crank levers 47, 48, 49 have different included angles which are suited to the movement of the beam to which they pertain. The links 45 are

capable of slight side movement in order to accommodate any side movement of the bricks against which the beams 41 may be pressing. The movements of the beams 41, as produced by their respective bell-crank levers 47, 48, and 49, will be proportional to the movement due to expansion from the rotation of the main roof skew back buttresses 11 and also to the relative positions of the individual beams on the roof surface. In these circumstances there should be no stress or load between the beams 41 and the bricks of the roof arch.

Should any one section of the roof become heated more than the other sections, local excessive expansion and consequently alteration of roof curvature would tend to occur; flattening in a hot part, for example, would tend to cause bulging in a cooler part. By providing the beams 41, however, which under normal conditions just touch the roof, should local overheating occur, the cooler parts of the roof tending to bulge would be supported by beams 41 so as to resist the bulging pressure, whilst in other parts tending to flatten the roof would move away from the beams 41. Change of shape of the roof is particularly liable to occur when the roof wears thin in parts, in which case the thicker and heavier portions tend to flatten and the thin parts to bulge.

Whatever may be the cause tending to change the shape of the roof, the occurrence of an undesired change of shape will be prevented by the beams 41.

It should be clearly understood that the invention is not limited to the details of construction hereinbefore described and illustrated, which are capable of many modifications and variations within the scope of the invention as defined in the appended claims.

1. In a furnace of the class described, the combination of a supporting structure, a roof arch associated therewith, supporting levers at opposite ends of said arch, buttresses for said arch received by one end of each of said levers, pivot means intermediate the ends of said levers, suspension means connected to said pivot means for supporting said levers and arch from said supporting structure, and connecting means connecting the ends of said supporting levers opposite the arch receiving ends for accommodating inward and outward movements of said arch ends with respect to each other due to expansion and contraction of the arch.

2. Arch supporting means as set forth in claim 1, wherein the suspension means is slidably connected to the supporting structure for vertical adjustments of the arch.

3. Arch supporting means as set forth in claim 1, combined with resistance means extending along the top of the arch for yieldably contacting the arch at spaced points therewith to resist buckling of the arch during expansion, supporting means for suspending said resistance means from the supporting structure, and means for connecting said resistance means to the lever connecting means to raise and lower the resistance means proportionately to arch expansion.

4. A furnace arch support of the class described comprising in combination a supporting structure composed of spaced uprights or stays and connecting beams therefor, pivoted suspension levers

mounted on said supporting structure at front and back of the arch, an arch having buttresses at its front and back seated in the end of each suspension lever at one side of its pivot, connecting means intermediate the respective front and back suspension levers, including a rockable lever connected at one end to each front pivoted suspension lever aforesaid and at its other end to one end of said connecting means, each said rockable lever being connected to one end of the associated pivoted suspension lever at the opposite side of the pivot from the arch buttress, whereby movement of a front pivoted suspension lever in one direction causes movement of the corresponding back suspension lever in the opposite direction.

5. A furnace arch support as set forth in claim 4, combined with means for resisting the movement of the pivoted suspension levers due to arch expansion in a progressively increasing degree as the expansion increases.

6. A furnace arch support of the class described comprising, in combination, a supporting structure composed of spaced front and back uprights and connecting beams therefor, an arch arranged between the front and back uprights, supporting levers along the front and back of the arch in one end of which the buttresses of the arch are seated, pivot means for each of said supporting levers, adjustable suspension means connected to the said pivot means and to the supporting structure, a rocking lever connected to the free end of each front supporting lever and to the suspension means, tie rods connected to said rocking levers at one end and to the free ends of the back supporting levers, and weight supporting means connected to the back supporting levers and to the associated suspension means.

7. A furnace arch support as set forth in claim 6, wherein the weight supporting means comprises a bell-crank lever having short and long lever arms, the short arm being connected to the associated back supporting lever and weights being suspended from the longer arm.

8. A furnace arch support as set forth in claim 6, combined with spaced beams extending longitudinally above the roof arch, brackets depending from the beams connecting the front and back uprights and bell-crank levers mounted on said brackets, one arm of each of which is connected to an associated longitudinal beam and the other arm of each of which is connected to an associated tie rod.
